His Attorney.

UNITED STATES PATENT OFFICE.

JACOB ALVIN HYLE, OF ST. LOUIS, MISSOURI, ASSIGNOR TO RAILWAY TIE SUPPLY COMPANY, A CORPORATION OF DELAWARE.

METALLIC RAILWAY-TIE.

1,385,241.

Specification of Letters Patent. Patented Mar. 30, 1920.

Application filed September 30, 1919. Serial No. 327,449.

To all whom it may concern:

Be it known that I, JACOB ALVIN HYLE, a citizen of the United States, residing at St. Louis, in the county of St. Louis and State of Missouri, have invented certain new and useful Improvements in Metallic Railway-Ties, of which the following is a specification.

This invention relates to an improved metallic railway tie and means for securely fastening the track rails in their proper position on the ties of steam and electric railroads.

The main object of this invention is to provide a strong, durable, economical and thoroughly efficient metallic railway tie, possessing the required strength to readily withstand all the usual strains to which the tie is normally subjected when in use, and which is so constructed as to materially increase the longevity of the same.

Another object of the invention is to provide a simple construction of metallic railway tie in connection with wooden blocks, said blocks constituting a resilient support for the track rails, and a reliable insulation of the rails so that said rails may serve as efficient conductors in the usual automatic signaling systems.

A further object of the invention is to so construct the improved railway tie that the number of ties required per mile of road will be considerably reduced.

Still further objects of the invention are to so construct the tie and blocks, that the wooden blocks may be easily and readily removed and new blocks inserted or replaced by a single employee and without removing the tie, or in any manner whatever disturbing the position of the track rail or ballast beneath the tie; to safely and securely fasten the wooden blocks to the tie, whereby absolute safety in the gage of the track rails is always maintained, and to secure the track rails in their proper position upon the wooden block by means of the ordinary railway spike now in use and employed for securing the track rails to a wooden tie; to provide means in connection with the tie and blocks to insure the seating of the blocks securely in contact with the base of the tie at all times when bolted to the tie, said means also serving to prevent the wooden blocks from spreading apart under the strain to which they are subjected, and to provide the

outer face of each block with a strong and durable clamping plate which serves not only to hold each wooden block in its proper position with respect to the metallic tie, but also serves to compress the fibers of the wooden block to such an extent as to prevent splitting of the block where the track rail securing spikes are driven therein, said clamping plates being provided with means which prevents any vibratory or swinging movement of the blocks or plates.

The foregoing and such other objects as may appear from the ensuing description are attained by the means hereinafter more fully described and by the combination, construction, arrangement and location of the parts such as illustrated in the accompanying drawings and particularly pointed out in the claims appended hereto, it being understood that slight changes in the form, proportions, and minor details of the construction may be resorted to without departing from the spirit or sacrificing any of the advantages of the invention.

In the accompanying drawings which form a part of the specification, it will be seen that:

Figure 1, is a perspective view of the improved tie.

Fig. 2, is an end view of the same.

Fig. 3, is a detail showing the wooden blocks detached from the tie.

Fig. 4, is an enlarged detail side elevation showing the block clamping plate detached.

Fig. 5, is an enlarged detail showing the inner face of the clamping plate shown in Fig. 4, and

Fig. 6, is an enlarged view showing one of the block securing pins detached.

Similar numerals of reference are employed to designate corresponding parts throughout the several figures of the drawings.

In carrying out this invention, I provide a railway tie of suitable or desirable dimensions throughout its length and breadth and the metallic portion of said tie with which this invention is embodied in the form illustrated may be made from any suitable metallic material, but is preferably made from cast-off or worn-out steel railway track rails by cutting through the web portion of the rail immediately below the tread portion, and then rolling the web and base portion thereof until it is caused to as-

sume the form illustrated in the drawings, which consists of a flat laterally extended base portion 1, and a central vertical member 2, extending the entire length of the 5 tie.

It will be observed that the track rails are seated and rest upon the upper surface of the wooden blocks 5, there being two blocks on each side of the vertical member 10 of the tie, and two blocks near each end of the tie, each block having straight vertical faces, with the lower surface of each block resting in contact with the upper surface of the laterally extended base portion 15 of the tie, the upper surface of each block extending a suitable distance above the vertical top portion of the tie in order to thoroughly and effectually insulate the track rails from the tie, and to form a wide bearing surface at the upper portion thereof for 20 the base of the track rail. The size of the blocks is sufficient to furnish the required strength to support the track rails and retain the rail fastening means such as spikes 25 of the type ordinarily employed in securing the track rails to a wooden tie, which spikes are usually driven into the wooden blocks with the head portion of each spike overlapping and in contact with the upper surface 30 of the base of the track rail.

The wooden blocks such as utilized are inexpensive, since the ends of logs, the well preserved portions of cast-off wooden ties, and other pieces of wood are used up which 35 would ordinarily be classed as waste material, and said wooden blocks are first preferably impregnated with crude oil, creosote, or any other desirable preservative preparation to increase their longevity and durability, they are formed rectangular in cross-section, and adapted to fit accurately in contact with the base portion and against the central vertical member of the tie, the dimensions of the blocks being uniform so 40 that they may be turned upside down or either side may be utilized as the top or track rail supporting surface.

The improved fastening means preferably employed for firmly and securely 45 clamping each block to the body portion of the tie and in contact with the base of the tie comprises a single headed bolt 6, of sufficient strength, screw-threaded at one end thereof, and a single clamping plate 7 for 50 each block, which is adapted to contact with the outer side face of each block, each of said plates being provided with a plurality of integral inwardly extended spurs 8, which are embedded into the block when 55 the plates are securely clamped against the outer face of each block, by the securing nut 9 fitted to the screw-threaded end portion of the securing bolt 6, and resting against the outer flattened surface of each plate. Each

securing bolt 6, is passed through an opening 65 6' formed centrally through each block and through a corresponding opening formed in the vertical member 2, and each clamping plate is fitted to the bolt at each end thereof, so as to rest in contact with 70 the outer side of each block, said plate extending a suitable distance at either side of the bolt and from the bottom of each block to a point near the top of each block, but terminates at a sufficient distance below the 75 base of the track rail to prevent accidental contact with the said rail under all conditions, thereby eliminating all possibility of electrical contact between the track rails and the block securing means. 80

In the inside face of each block, which portion rests in contact with the vertical member, are formed two holes or recesses 11, which holes or recesses extend to a suitable distance within each block, and are 85 adapted to register with corresponding openings formed through the vertical member, each opening being adapted to receive a steel pin 12, which passes through said opening and into the hole or recess 11 in 90 each block, said pins serving, during the operation of clamping the blocks securely to the metal tie, to maintain the lower surface of each block in contact with the upper surface of the base of the tie, thus preventing 95 any tendency of the blocks to move upward and downward during the passage of the rolling stock over the track rails, said pins also serving to prevent any lateral movement or spreading of the blocks side- 100 wise or outward in the event that the securing bolt should become loose or broken, as will be readily understood.

It will be seen that each wooden block projects a suitable distance above the metal 105 portion of the tie, in order to insure a safe insulating medium and preventing interference with the use of electric signaling means, and the laterally extended base portion of the tie upon which the wooden blocks are 110 supported forms a widened tie, thereby materially reducing the number of ties required per mile of roadbed, and it is more readily retained in its proper relative position than the narrower ties, and while the base of the 115 track rail is shown seated upon the upper surface of the wooden blocks, it will be obvious that any suitable or desirable plate may be used to rest upon the blocks to form a seat for the track rail base.

It will also be perceived that each block is provided with a central opening there-through, and when the clamping plate is secured to the outer side wall of each block by the securing bolt and nut the fiber of the 125 wooden blocks will become tightly compressed and prevented from splitting when the rail fastening spikes are driven therein, and the blocks are provided with means

whereby they are fixedly held in contact with the base of the tie, thereby preventing any up and down movement with relation to said base with the wave motion of the rail 5 during the passage of the rolling stock over the track rails, and there can be no shifting of the blocks without moving the entire track rail supporting means, thus insuring and always maintaining the proper gage of the 10 track rails and alinement of the track.

It will be understood that the space between the wooden blocks and at the outer end of said blocks is filled up with track ballast which assists in preventing any lateral, longitudinal or skidding action of the 15 railway ties during the strains to which they are usually subjected.

While I have shown two pins fitted through the openings formed in the central 20 member and into the holes or recesses formed in each block, it may be necessary to use but a single pin to prevent the spreading outward of the block but it is preferred to employ two pins, in order to force the 25 blocks into fixed contact with the rail base and maintain the blocks in such position when securely clamped to the metallic tie.

It will be perceived that each block 30 clamping plate 7 is hollowed out somewhat in its inner surface and formed with a solid integral portion 10 extending entirely around the plate, said plate being also provided with a thickened central portion having a flattened outer surface for the reception 35 of the securing nut 9, and each end of the plate is provided with an integral outward and upward and an outward and downward extension 13, terminating substantially in transverse alinement with the 40 rail securing spikes, said plates so tightly compressing the fibers of the blocks together when securely fastened to the blocks, as to practically eliminate all tendency of the 45 blocks to split when the rail securing spikes are driven therein, and the said plate is so formed as to prevent its contact with the rail and to prevent contact with anti-rail creepers when used in connection with the tie.

50 Having thus described my invention what I claim and desire to secure by Letters Patent is:—

1. A metallic railway tie having a flat base portion, and a central vertical member 55 provided with a plurality of openings adapted to receive securing bolts, two wooden blocks recessed on their inner faces and resting on said base at each side of the central member, and means passing through 60 openings formed through the central member and within the recessed face of each block for securing the blocks in fixed contact with said base and for preventing spreading of the said blocks.

65 2. A metallic railway tie having a flat

base portion, and a central integral vertical member provided with a plurality of openings therethrough, two wooden blocks supported on said base at each side of the central member, each of said blocks having 70 recesses formed in its inner face, means passing through the blocks and central member for securing the blocks to the body portion of the tie, and means passing through openings formed through said central member 75 and within the recesses formed in the blocks for securely holding the blocks in fixed contact with the base of the tie and for preventing spreading of the said blocks.

3. A metallic railway tie having a flat 80 base portion, and a central vertical member provided with a plurality of openings therethrough, two wooden blocks secured to the upper surface of said base at each side of the central member, each of said blocks having 85 recesses formed in its inner face, means passing through the central member and each block for securing said blocks to the tie body, and means passing through openings formed in said central member and 90 within the recessed portion of each block for securing the blocks fixedly against the upper surface of the base portion and preventing outward movement of the blocks.

4. A metallic railway tie comprising a 95 flat base and an integral central vertical member, wooden blocks supported upon said base at each side of the central member, each block being recessed in its inner face, means for securing said blocks to the body 100 portion of the tie, and means passed through openings in the central member and within the recessed portion of each block for holding each block in fixed contact with the said base and for preventing spreading of the 105 blocks.

5. A metallic railway tie comprising a flat base portion and an integral central vertical member extending throughout the length of the tie, wooden blocks supported 110 upon the base at each side of the central member, each block having a central opening formed therethrough, a threaded securing bolt adapted to pass through said opening and through an opening formed in the central member, a securing nut fitted to the threaded end of said bolt, and means passed through openings formed in the central member and into openings formed in each block for fixedly holding the blocks 115 120 in contact with said base and to prevent outward movement of the blocks.

6. A metallic railway tie comprising a flat base and an integral central vertical member, wooden blocks resting upon the 125 base at each side of the central member, each block having a central opening formed therethrough, means for securing said blocks to the body portion of the tie, and steel pins passed through openings formed 130

- in the central member and into openings formed in each block to secure the block in fixed contact with said base and to prevent the outward spreading of said blocks.
- 5 7. A metallic railway tie comprising a flat base with an integral central vertical member, wooden blocks supported upon the base at each side of the central member, each block having a central opening therethrough,
- 10 10 a securing bolt with a threaded end passed through each block, a metal reinforced

clamping plate resting in contact with the outer side face of each block, a securing nut fitted on the threaded end of said bolt and adapted to contact with the reinforced surface of the clamping plate, and steel pins passed through openings formed through said central member and into each wooden block for securing each block in fixed contact with said base and to prevent outward spreading of the blocks. 15

JACOB ALVIN HYLE.
